UNITED STATES PATENT OFFICE.

CARPENTER J. QUAY, OF MEADVILLE, PENNSYLVANIA.

TRAIN-ORDER HOLDER.

1,087,828.

Specification of Letters Patent.

Patented Feb. 17, 1914.

Application filed August 11, 1913. Serial No. 784,219.

To all whom it may concern:

Be it known that I, CARPENTER J. QUAY, a citizen of the United States, residing at Meadville, in the county of Crawford and 5 State of Pennsylvania, have invented new and useful Improvements in Train-Order Holders, of which the following is a specification.

My present invention pertains to what 10 have come to be commonly known as train-order holders.

Train-order holders have heretofore been made of wood because of the cheapness and lightness of such material, and it has been 15 found desirable to utilize a single piece of wood in the formation of the hoop and the shank comprised in the holders. It has been found difficult, however, because of the scarceness of suitable wood, to procure pieces 20 long enough to form both the hoop and shank or handle.

One of the objects of my present invention is to provide a train-order holder the shank or handle of which is formed of pieces of 25 wood rigidly and strongly joined together.

The invention also contemplates the provision of improved means for strongly connecting the end of the hoop to the major portion of the piece of wood, and to clasp 30 messages or the like against the holder, and this without materially increasing the cost of production of the holder.

With the foregoing in mind the invention will be fully understood from the following 35 description and claims when the same are read in connection with the drawings, accompanying and forming part of this specification, in which:

Figure 1 is a side elevation of my improved train-order holder. Fig. 2 is a horizontal section, on an enlarged scale, taken in the plane indicated by the line 2—2 of Fig. 1. Fig. 3 is an enlarged detail side elevation showing the combined tie and mes- 45 sage-clamp. Fig. 4 is an enlarged longitudinal section illustrative of the simple and efficient manner in which I rigidly join the sections of the shank or handle of the hoop.

Similar numerals of reference designate 50 corresponding parts in all of the views of the drawings.

The hoop 1 of the holder and a portion or section 2 of the holder shank or handle are formed of a single piece of wood, which may 55 be of circular or any other suitable form in cross-section without involving departure

from my claimed invention. In the formation of the hoop it is bent, and its end portion is arranged transversely across the straight major portion, as shown in Figs. 1 60 and 3, the said end portion of the hoop is preferably, though not necessarily, connected in fixed manner to the straight major portion through the medium of a brad or nail 3, the said connection being reinforced 65 and strengthened by the combined tie and clamp hereinafter definitely described.

For the reason hereinbefore set forth, the handle or shank of the holder comprises the section 2 and a wooden section 4, which may 70 be of any desired length without affecting my invention. The sections 2 and 4 are arranged in aligned relation, and their beveled end portions 5 and 6 are lapped, as shown in Fig. 4, so that the section 4 presents the appearance of a continuation of the section 2. It will also be seen by reference to Fig. 4 75 that each beveled and lapped portion 5 and 6 is connected to the other by one or more brads or nails 8, and that the said brads or 80 nails serve the additional function of securing in position a metallic sleeve or ferrule 9, which has for its function to surround and hold together the lapped portions 5 and 6, so as to render the shank or handle as a 85 whole quite as stiff and strong as a one-piece shank or handle. It will further be observed in this connection that the manner of joining the sections 2 and 4 is extremely 90 simple and inexpensive, notwithstanding its manifest efficiency and durability.

The combined device hereinbefore referred to, comprises a spring clamp 10, and a tie 11. In forming the said device, a piece of wire, possessed of sufficient resiliency, is bent 95 into loop-form, and the bight of the loop is flared, as indicated by 12. The inner end portions of the loop are made to straddle the end portion of the hoop, at a point within the straight major portion, and said end 100 portions are then coiled about the straight major portion, as indicated by 13, after which they are coiled about the end portion of the hoop, at a point outside the straight major portion, as indicated by 14, and at 15 their ends are bent into interlocked or other suitable connection. At the base of the loop-shaped clamp 10, the sides of the same are preferably connected by a cross wire 16, which bears normally against the end portion 110 of the hoop, as illustrated. I would also have it understood here that in making the

connection between the end portion of the hoop and the straight major portion, I prefer to employ a supplemental wire 18. Said wire 18 is bent one or more times about the 5 straight major portion, and also about the end portion of the hoop, and its ends are twisted or otherwise connected as indicated by 19. From this it follows that the combined clamp and tie, especially when supplemented by the wire 18, will assist materially 10 in the strong and durable connection of the end portion of the hoop to the straight major portion.

When it is desired to clamp a message or 15 the like against the hoop, the said message is folded and is interposed between the clamp 10 and the opposed portion of the hoop, in which position it will be securely held against casual displacement.

20 The manner of using my novel train-order holder is the ordinary one, well known in the art, and need not therefore be described.

Having described my invention, what I 25 claim and desire to secure by Letters-Patent is:

1. A train-order holder comprising a hoop and a shank or handle section formed of a single piece of wood; the end portion of the hoop being joined to the shank or handle 30 section, and the end of the shank or handle section being beveled, a second handle section arranged in alined relation to the first-named handle section and having a beveled end opposed to and lapped with the beveled 35 end of the first-named handle section, a metallic sleeve surrounding the beveled and

lapped portions of the wooden handle sections, and brads extending through said sleeve and into said lapped portions of the wooden sections, substantially as specified. 40

2. A train-order holder comprising a hoop and a shank or handle section formed of a single piece of wood; the end portion of the hoop being joined to the shank or handle section, and the end of the shank or handle 45 section being beveled, a second handle section, of wood, arranged in alined relation to the first-named handle section and having a beveled end opposed to and lapped with the beveled end of the first-named handle 50 section, and a smooth bore metallic sleeve surrounding and fixedly connected with the beveled and lapped portions of the wooden handle sections.

3. A train-order holder comprising a hoop 55 and a shank or handle portion formed of a single piece of wood; the end portion of the hoop extending transversely across the shank or handle portion, and a combined clamp and tie, formed of wire and having a loop-shaped portion to form a clamp that normally bears in yielding manner against the hoop, and further having coils that embrace the shank or handle portion and the end portion of the hoop. 60

In testimony whereof I have hereunto set my hand in presence of two subscribing witnesses.

CARPENTER J. QUAY.
